UNITED STATES PATENT OFFICE.

SAMUEL J. SAVEREID, OF HUXLEY, IOWA.

DEFLECTOR PLATE FOR STOVES.

Application filed June 3, 1925. Serial No. 34,610.

The object of my invention is to provide a deflector plate for stoves of simple and durable, yet inexpensive construction.

A further object is to position such a plate in a stove or furnace so that it will baffle the flames and smoke from the fire, and thereby radiate more heat from the flames to the shell of the stove and will also be an aid to consuming the smoke.

Still a further object is to provide tubes on the plate to aid in further baffling the heat.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of my improved baffle plate.

Figure 2 is a section of one of the tubes taken on the line 2—2 of Figure 1.

Figure 3 is a side view of my device shown installed in a heating stove, the stove being shown in section.

Figure 4 shows an additional means of fastening my baffle plate to the shell of the stove; and

Figure 5 is a slightly modified form of fastening for the plate.

In the accompanying drawings, I have used the reference numeral 10 to indicate the baffle plate, which is made the same shape as the stove it is to be installed in so that it closely fits the shell of the stove at all points.

Rods 11 are secured to the plate 10 such as by spot welding, as at 12, or any other suitable manner.

The ends of the rods 11 are bent up at 13 and are threaded to receive the nuts 14. The ends of the nuts 14 are rounded as at 15 so that when screwed outwardly, they will cause dents 16 in the stove shell 17, and thus securely hold the plate 10 in any desired position in the shell.

I mount the rods 11 on top of the plate 10 so that the nuts 14 may be easily reached and adjusted by inserting a wrench through the opening 18, which is found on most stoves.

In the plate 10 are openings 19 into which tubes 20 having flanges 21 are inserted. The

tubes 20 remain therein, due to their weight and are prevented from falling through the opening 19 by the flanges 21.

A screen 22 is placed over the end of each tube 20, and held thereon by the ends 23 being turned under the flange 21 or by any other suitable manner such as spot welding.

In installing my device, the entire assembly is inserted through the door opening 24, and the nuts 14 are then screwed outwardly 65 and engage the shell 17.

In case where the stove has no opening 18, the plate 10 may be turned over and the tubes 20 inserted from the opposite side so that they are suspended through the openings 19. The nuts 14 may then be adjusted through the door opening 24.

As is apparent upon inspection of Figure 3, the plate 10 is positioned a distance above the fire 25 so that the longest possible tubes 20 may be used, and still leave enough space above the plate so as not to restrict the passage of smoke and gas from tubes 20 to the chimney 26. The tubes must, however, be short enough not to interfere with the admission of fuel through the door opening 24.

It will thus be seen that I have provided a baffle plate for baffling the smoke and gas, which, in the ordinary stove, are drawn directly from the fire 25 and up the chimney 26, thereby excessively heating the back part of the stove 17 and the chimney 26, and causing a large percentage of the heat to be discharged from the chimney into the atmosphere.

When the fire is being started with light material, such as paper or kindling, small particles of this material on fire are apt to be drawn up the chimney and sometimes fall on the roof and ignite it.

By my arrangement, the smoke and gases rise, due to the heat from the fire 25, and strike the plate 10. They are then deflected and drawn downward and toward the front of the stove and then into the lower ends of the tubes 20, due to the draft created by the fire and the chimney.

Small particles of paper or kindling are stopped by the screens 21. The smoke and gases then travel to the back of the stove 105 and up the chimney 26.

By thus making the smoke and gases follow a long path in the stove, more time is given for the heat in them to be radiated through the shell 17. This long path also 110

causes the fire to more completely consume the smoke and gases and thereby cause greater radiation.

By positioning the tubes 20 near the front part of the stove, the smoke and gases are drawn to the front of the stove, and the front part heats more than the back part, which is desirable in that heating stoves are usually placed with the back part near the wall and the front part facing the interior of the room.

By having the plate 10 over the back part of the fire, the smoke and gases cannot assume a direct path to the chimney.

15 If desirable, screws 27 may be inserted through holes made in the shell 17 and screwed into the nuts 14.

In manufacturing a stove having my deflector plate as a part thereof, bars 28 could 20 be substituted for the rods 11. The bars 28 have ears 29 for riveting them to the shell 17 through the holes 30.

In this case, the plate could be merely laid on the bars 28 and the tubes 20 would 25 prevent any turning of the plate 10. The plate 10 and tubes 20 would then be removable.

I have found that a stove having my device installed therein delivers a more steady 30 heat and greatly reduces the fire hazard from sparks even when the screens 22 are not used. It also effects a great saving in fuel used.

Some changes may be made in the con-

struction and arrangement of the various 35 parts of my invention, without departing from the real spirit and purpose of my invention and it is my intention to cover by my claims, any modified forms of structure or use of mechanical equivalents, which may 40 be reasonably included within their scope.

I claim as my invention:

1. A deflector for heating stoves comprising a plate suspended above the fire therein, openings in substantially the front half of 45 said plate and tubes secured in said openings and extending downwardly therefrom.

2. In combination with a stove or the like, a plate substantially the same diameter and outline as the inside of the shell of 50 said stove, means for securing said plate in said shell, openings in substantially the front half of said plate, tubes in said openings extending downwardly therefrom and screens covering one end of each of said 55 tubes.

3. In combination with a stove having a shell, a plate substantially the same diameter and outline as the inside of said shell, means for securing said plate in said shell, 60 said means comprising screw threaded rods fastened to said plate and terminating adjacent the shell of the stove, nuts on said rods for engaging and protruding into said shell, openings in the front of said plate 65 and tubes extending downwardly therefrom.

Des Moines, Iowa, May 27, 1925.

SAMUEL J. SAVEREID.
